MEDICINAL COMPOUND

Edward C. Moore, Flushing, N. Y.

No Drawing. Application September 23, 1933,
Serial No. 690,765

5 Claims. (Cl. 167—55)

My invention relates to improvements in the preparation of therapeutic oil-containing medicaments generally and more particularly to a medicament adapted for enteric assimilation.

5 An object of my invention is to provide a medicament comprising an admixture of certain compounds adapted, when prepared as herein disclosed, to react with the intestinal fluids so as to produce a valuable therapeutic effect.

10 Heretofore it has been proposed in preparing oils for medicinal use, to emulsify the oil, such as castor or cod liver oil, in the presence of an oxide of magnesia and reduce the resulting solid mass to a powder. It has also been proposed to 15 provide medicaments devised for intestinal assimilation in the form of capsules having enteric coatings.

The present invention is directed to a medicament, capable of intestinal assimilation rather than the means by which it may be administered or by which it may be carried past the acidulated 20 gastric juices of the stomach to the alkaline secretions of the intestinal tract. I have discovered that oils such as the oil of santon may be better utilized as a therapeutic, when admixed with a resinous acid, such as abietic acid. Abietic acid, also known as sylvic acid is, in the pure state, a yellowish crystalline solid, having the empirical formula $C_{20}H_{30}O_2$. It is dibasic and may be obtained from the resin of the fir species, colophony, 25 of which the compound abietic anhydride $C_{14}H_{26}O_4$ is the chief constituent.

While the yellow leaflet crystals of abietic acid have a melting point of 182° C., I have found that when mixed with the oil of santon, a composite 30 semi-solid mass of paste like consistency is produced at a much lower temperature.

Oil of santon or sandal oil, also known as santon-wood oil, is a thick yellow volatile liquid oil consisting substantially of three structural isomers of santonine, the terpene santol, santol, and the ester santolyl salicylate. It is derived by steam distillation from *santalum album* and the medicinal properties which it exhibits are probably due to the presence of the salicylate ester. The 35 oil of santon is a valuable remedy in the treatment of chronic and subacute inflammations and particularly in the treatment of cases wherein the first period of acute inflammation has passed. It 40 is capable, in properly prescribed doses of causing systemic excitement.

Having prepared the semi-solid admixture of the resinous acid and oily ester, I add powdered extract of licorice or glycyrrhizin $C_{44}H_{66}O_{18}$, glycerine and light oxide of magnesia. The amorphous

oxide derived from calcining the basic carbonate is found preferable to the crystalline magnesium oxide.

This semi-solid admixture has the proper consistency around 16 to 18° C. to permit the application of an enteric coating. I have also found that the physical state of the resultant preparation is such that a firm gelatinous coating can be applied thereto and that capsules can be made in this way, which will be useful under very hot climatic conditions. Alternatively, the compound permits the use of a white or other colored enteric subcoating over which a color or colorless gelatin coating may be placed.

The resultant medicinal effects and unobvious therapeutic action arising in part from the intestinal assimilation of an oil, such as the one herein suggested or others of similar medicinal properties, is due to the action in the intestinal tracks of the alkaline secretion constituent, potassium bicarbonate. This compound, hydrolyzing basicly, forms the alkali salt of the resinous acid, as in this case, potassium abietate. The alkali abietate is an emulsifying agent and together with the extract of licorice or specifically the glycyrrhizin assures complete emulsification of the oil. Thus at the place of assimilation, there is oil emulsification with the composite therapeutic effects of the oil and alkali salt. It will be appreciated that the process of disintegration of the compound in the intestinal tract is gradual and permits a better toleration of the medication, through a more uniform and complete assimilation of the santon oil.

While my invention is directed primarily to a medicament comprising an oil and a resinous acid, the acid upon reaction with the alkaline intestinal secretions producing an emulsifying agent for the oil and thus providing for its bodily assimilation, the following table of percentage range of constituents which I have found particularly satisfactory is given without limitation as to compounds or proportions:

Oil of santon	20%	to	33 $\frac{1}{3}$ %	45
Abietic acid	20	to	33 $\frac{1}{3}$ %	
Glycerine	3	to	5	
Light magnesia oxide	10	to	20	
Extract of licorice	15	to	25	

While I have disclosed the preferred embodiment of my invention, I wish it to be understood that these are but preferred embodiments which typify others in which may be incorporated the underlying features of this invention. Modifications may be made in the proportions of the 50 55

ingredients used, within the spirit and scope of my invention, and such modifications are intended to be covered by the appended claims.

What I claim is:

- 5 1. A medicament comprising the oil of santal and a resinous acid capable of reacting with the alkaline intestinal secretion so as to emulsify said oil.
2. A medicament comprising a pasty mass including a homogeneous admixture of oil of santal and abietic acid.
- 10 3. A medicament comprising the oil of santal, abietic acid and extract of licorice.

4. A medicament comprising oil of santal, abietic acid, extract of licorice, light oxide of magnesia and glycerine.

5. A process for the preparation of a medicament, comprising intimately admixing oil of santal and abietic acid in the presence of extract of licorice, glycerine and light oxide of magnesia, the ingredients being so proportioned as to produce a paste like mass and covering the resulting semi-solid mass with a gelatinous coating. 5 10

EDWARD C. MOORE.
